UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,189,447.

Specification of Letters Patent.

Patented July 4, 1916.

Original application filed December 10, 1908, Serial No. 466,836. Divided and this application filed September 16, 1914. Serial No. 861,936.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

My invention relates to computing machines of the kind in which numbers are temporarily set up and later carried into computing wheels.

My invention is herein illustrated as applied to a combined typewriting and computing machine of the general kind shown in the United States patent to Hans Hanson, No. 905,421, dated December 1, 1908. In said patent a typewriting machine is provided with the usual carriage, and the 20 computation device connected thereto includes denomination or computation bars, which are normally in ineffective position. Said bars are however, by the travel of the typewriter carriage brought into effective 25 position one at a time, with the result that if the numeral keys are operated, the numeral key depressed will set up on the computation bar in effective position, a pin representing a digit printed by said numeral 30 key. After a series of digits have thus been set up to represent a number, a general operator is caused to move forward, engage the depressed pin and drive the computation bars thereby, each to an extent depending 35 on the pin depressed. In thus being driven each turns its computing wheel to cause the number represented by the depressed pin to be carried into its wheel. This general operator is then returned to 40 its normal idle position, and in so returning restores the computation bars and the pins thereof to their normal position.

The present invention is especially designed for making such machines proof 45 against errors in operation, and for this purpose is provided with devices for preventing the operation of the numeral keys and through them of the traveling carriage, while the general operator is standing away 50 from its normal position. My invention, therefore prevents attempted setting-up of numbers, through the medium of the keys

and carriage while the computation bar is in improper position.

Other features and advantages will here- 55 inafter appear.

This application is a division of my application No. 466,836, filed December 10, 1908.

In the accompanying drawings: Figure 1 60 is a sectional side view of an Underwood-Hanson combined typewriting and computing machine, showing so much thereof as is convenient to illustrate my invention as applied thereto; also showing the general operator part way through one of its movements. Fig. 2 is a fragmentary view of part of Fig. 1, showing normal position of the parts. Fig. 3 is a plan view of part of Fig. 2. Fig. 4 is a perspective view showing 70 means for locking the numeral keys against depression. Fig. 5 is a plan view of an Underwood typewriter machine to which my invention is applied. Fig. 6 is a plan view of the computing mechanism. 75

In the usual Underwood typewriting machine, numeral keys 5 and alphabet keys 4 depress their key-levers to cause type-bars 3 to swing upwardly and rearwardly against the platen 14, mounted in the usual 80 traveling carriage 2, to cause types to print thereon. The keys as they approach the platen operate a universal bar, not shown herein, forming part of an escapement mechanism, which also includes an escapement wheel 2^a and a pinion 2^c to permit the typewriter carriage to be drawn along a step at a time by the usual spring barrel, not shown herein. The pinion 2^c controls the typewriter carriage by the usual rack 90 bar 2^a, with which it meshes.

As the typewriter carriage travels along, it moves computing or preliminary representation denominational bars *c*, which normally stand in an ineffective or idle position, so as to lift said bars and bring them within the range of pin-setting bars *b*. Said pin-setting bars are each connected to its own numeral key with the result that if any numeral key is depressed, its pin-setting bar will be depressed at the same time and depress the corresponding pin *c*^a on whichever rack bar at the moment is raised into effective position. To bring the com- 95 100 105

putation bars *c* within the range of the pin-setting bars *b*⁷, they are lifted upwardly by means of a dog or decimal order selector *f*, settable on the typewriter carriage. To lift them up one at a time, the dog *f* travels *seriatim* under a series of jacks or levers *f*¹ pivoted on the fixed rod *f*¹⁵, with the result that the rear end of the dog *f* depresses *seriatim* the vertical rods *f*¹⁶ of which there is one for each jack *f*¹ and computation bar *c*. Whenever a rod *f*¹⁶ is depressed, it rocks its lever *f*¹⁶ on which it rests, to cause said lever to lift up a linkage *f*²⁸ forming part of a transposition device, which in turn lifts the corresponding computation bar *c*. This transposition device is necessary, because the dog *f* is effective on the jacks *f*¹ beginning with the right-hand one, while in order to compute numbers in the usual manner it is necessary to begin with the left-hand numeral. To obtain this result, the linkages *f*²⁸ of the transposition device form parts of parallel motion devices, which also include lugs *f*²⁹, there being one lug for each computation bar *c*, and the levers *f*¹⁶ are of varying lengths so that each lever operates only its own linkage and therefore only its own computation bar.

The numeral keys operate their pin-setting linkages by stems *b* fast on the key-levers, said stems passing through a flange *b*² to guide them, and each stem *b* as it descends strikes on a rock arm fast on a linkage-operating shaft *b*⁶, thereby rocking said shaft and depressing the corresponding pin-setting bar *b*⁷. To enable the rock shaft *b*⁶ to thus depress the pin-setting arms each shaft *b*⁶ is provided with a rock arm *b*¹², which engages a bar *b*⁹, said bar *b*⁹ together with the pin-setting bar *b*⁷ forming a parallel motion device. The connections are such that the depression of a numeral key moves its pin-setting bar *b*⁷ practically vertically downward, thereby setting or depressing a pin on the lifted computation bar *c*. When a series of pins *c*⁵ has thus been depressed, one on each computation bar *c*, a general operator (or operating carriage) which includes a cross-bar *c*⁹ is drawn forward, by pulling on a handle *c*¹³, so that said bar in coming forward will strike the ends of any depressed pins, (like the right-hand pin in Fig. 1) and thereby drive the computation bars each to an extent depending on its pin depressed. As the computation bars thus move forward they operate number-bearing wheels or computing devices *a* by means of pinions *a*¹, thereby adding the numbers into said wheels, or devices.

The handle *c*¹³ drives the general operator by means of segments *c*¹⁴, which mesh with idle pinions *c*¹⁶, said pinions meshing in turn with rack bars *c*⁷ forming the side bars of the general operator. Said side bars *c*⁷, the cross-bar *c*⁹, and the second cross-bar

*c*¹⁰ together form the general operator, being a rigid rectangular frame. The bars *c* are returned by the cross bar *c*¹⁰ of the general operator on its return stroke. On the return stroke of the general operator, the wheels or devices *a* do not turn because of the pawl and ratchet connections not shown herein between them and the pinions *a*¹. At the very end of the return stroke of the general operator all of the set pins are restored to unset position by devices not shown herein.

In order to prevent the operative from attempting to set up pins when the general operator is not in its normal position, a lock is provided for automatically locking the numeral keys unless said lock is released by the general operator. To enable this to be done, the stems *b* of the numeral keys are provided with extensions *b*¹⁷, which are fast thereon and which when a numeral key descends enter between pendent swinging dogs *b*¹⁵, said dogs forming an array having a limited throw. This throw is sufficient to allow any single stem *b*¹⁷ to enter freely between its two dogs *b*¹⁵. When however, one numeral key is depressed so as to bring its extension *b*¹⁷ between two dogs *b*¹⁵, said extension takes up all the throw of said array of dogs and prevents the depression of any other numeral key, because the extension *b*¹⁷ of any other numeral key is unable to enter between its dogs *b*¹⁵. This simultaneous key-locking device, *per se*, forms no part of the invention claimed in the present application, and is fully disclosed in the application of which this is a division. This lock is utilized according to the present invention for preventing any numeral key from being depressed when the general operator is moved forward from its normal idle position. For this purpose there is provided between two dogs *b*¹⁵ at a point where it cannot interfere with any extension *b*¹⁷, a locking-arm *t*¹ which is fast on a rock shaft *g*⁶, said shaft being provided with a spring *t*², which normally tends to thrust the arm *t*¹ between the two dogs *b*¹⁵. When the general operator is in its normal position, the cross bar *c*¹⁰ thereof bears against the front of the extension *t* of the locking-arm *t*¹ and holds said arm clear of the dogs *b*¹⁵, with the result that the numeral keys can be freely operated. When, however, the general operator moves forward, the spring *t*² thrusts the arm *t*¹ between the dogs *b*¹⁵, and thereby closes up all the dogs *b*¹⁵ and locks the numeral keys against depression. Means are also provided for locking the transposition linkages *f*²⁸ against being raised when the general operator is not at normal idle position. For this purpose there is provided an arm *t*²² fast on the rock shaft *t*³ which when the general operator moves forward is forcibly brought down on top of the

linkages f^{23} , thereby locking them. To accomplish this, one of the side bars c^7 of the general operator is provided with a notch t^{25} , having a cam-shaped rear end, in which 5 notch normally rests a rock arm t^{24} fast to the rock shaft t^{23} . This arm is normally held down in place in said notch by a coil spring t^{26} embracing one end of the rock shaft t^{23} . When, however, the general operator 10 moves forward, the arm t^{24} rides out of its notch and swings the locking arm t^{22} forcibly down on the linkages f^{23} . This not only locks said linkages and thereby prevents any computation bar c from being 15 raised, but also by means of the connections through the levers f^{16} , rods f^{15} , and jacks f^1 , said locking arm prevents the dog f from moving any jack and therefore prevents the typewriter carriage from feeding past any 20 jack. It is impossible therefore for any operative to wreck a machine by attempting to set up numbers when the general operator has been partly but not completely actuated.

Variations may be resorted to within the 25 scope of the invention, and portions of the improvements may be used without others.

Having thus described my invention, I claim:

1. In a recording computing machine, the 30 combination with computing devices having decimal orders, of a decimal order selector, transposing devices, for making the selective action of said selector effective on said computing devices in a direction opposite to the 35 travel of the selector, operating means adapted to be operated once for each line written by the typewriter, and means for forcing the transposing devices into normal positions when the operating means is actuated.

2. In a recording computing machine, the 40 combination with computing devices having decimal orders, of a decimal order selector, transposing bars for selecting the decimal 45 orders of the computing devices in a reverse direction to the travel of said selector, a movable arm for forcing said transposing bars into normal positions, and means for actuating said arm, substantially as described.

3. In a recording computing machine, the 50 combination with computing devices having decimal orders, of a decimal order selector, transposing bars, for selecting the decimal 55 orders of the computing devices in a reverse direction to the travel of said selector, actuating means for said computing devices, a rock shaft having an arm for forcing said transposing bars into normal positions, con-

60 nections between the said actuating means and said rock shaft, and common means for operating said computing devices and said rock shaft, substantially as described.

4. In a combined typewriting and com- 65 puting machine, the combination with type-

writer numeral keys, computing devices, a typewriter carriage, means controlled jointly from said keys and carriage for setting up numbers to be carried into said computing devices, means for carrying numbers into 70 said computing devices when so set, and means for preventing said keys and carriage from performing their setting-up functions while numbers are being carried into the said computing devices. 75

5. In a combined typewriter and computing machine, the combination with the numeral keys of the typewriter and printing devices operated thereby, of computing devices, actuating means therefor, and means 80 for locking said numeral keys in inoperative positions during the operation of said actuating means.

6. In a combined typewriting and computing machine, the combination with parts 85 in which numbers are temporarily set up, of computing devices into which the set up numbers are carried, a general operator for so carrying them, numeral keys for setting up the numbers, and means for locking said 90 numeral keys against actuation when said general operator has been partly but not completely actuated.

7. In a combined typewriting and computing machine, the combination with computing devices, numeral keys and keys for writing any desired words, said numeral keys also controlling said computing devices, of a general operator for carrying the numbers written by said last-mentioned keys 100 into the computing devices, and means for locking said last-mentioned keys only when said general operator is moved from normal position, leaving said other keys free to write words at this time. 105

8. The combination with computing devices and numeral keys, of a general operator for carrying numbers indexed on the numeral keys into said devices, means for preventing simultaneous depression of two 110 keys, and means associated therewith for locking all of the numeral keys when the general operator is moved out of normal position.

9. In a combined typewriting and computing machine, the combination with computing devices and typewriter numeral keys, of a general operator movable for carrying numbers written by said keys into said devices, a traveling carriage for determining 120 into which devices said numbers shall be carried, and means for preventing movement of said carriage by said keys while said operator is moved from normal position.

10. In a combined typewriting and computing machine, the combination with typewriter numeral keys and devices, of denominational members movable from ineffective to effective position to enable said keys to be effective thereon, a carriage for so moving 125 130

said members, a general operator for carrying numbers from said members into said wheels, and means for preventing movement of said carriage by said keys while said operator is moved from normal position.

11. In a combined typewriting and computing machine, the combination with typewriter numeral keys and computing devices, of denominational members movable from ineffective to effective position to enable said keys to be effective thereon, a carriage for so moving said members, a general operator for carrying numbers from said members into said wheels and means for preventing movement of said carriage while said operator is moved from normal position, through the locking of said keys.

12. In a combined typewriting and computing machine, the combination with typewriter numeral keys and computing devices, of denominational members on which numbers may be set up by said keys, said members being normally clear of said keys, a traveling carriage under the control of said keys, means operated by said carriage for lifting said members *seriatim* within the range of said keys, a general operator for carrying the numbers set into said devices, and a bar made effective by said general operator when moved from its normal position to positively hold said lifting means against actuation.

13. In a combined typewriting and computing machine, the combination with numeral keys, computing devices and a general operator, of a series of dogs coöperating with said keys to prevent simultaneous depression thereof, a lug normally tending to coöperate with said dogs to lock said keys against actuation, and means connected to said general operator to hold said lug ineffective while said operator is in its normal position.

14. In a combined typewriting and computing machine, the combination with computing devices, of numeral keys for setting up numbers to be carried into said computing devices, a general operator for carrying into said computing devices numbers set up by said keys, a bar forming part of said general operator, and a follower under control of said bar to positively prevent the setting up of numbers by said keys.

15. In a combined typewriting and computing machine, the combination with numeral keys and computing devices, of a general operator for carrying numbers written by said keys into said devices, connections between said typewriting mechanism and said computing mechanism, a member effective to lock said connections, a spring normally tending to make said member effective, and means forming part of said gen-

eral operator for normally holding said member ineffective. 65

16. In a combined typewriting and computing machine, the combination with numeral keys and computing devices, of dogs for preventing simultaneous depression of said keys, denominational members on which 70 said keys are effective, a general operator for causing said denominational members to compute, and means controlled by said general operator to make said simultaneous depression dogs effective to lock all the keys, 75

17. In a computing machine, the combination with a single array of numeral keys and a traveling carriage, of denominational members on which said keys are effective in a direction opposite to the travel of said 80 carriage, a transposition device for causing said carriage to make said keys thus effective, a general operator for causing said denominational members to compute, and means effective on said transposition device 85 operated by said general operator to render said device ineffective when said general operator is moved from its normal position.

18. In a combined typewriting and computing machine, the combination with numeral keys and computing devices, of denominational members on which numbers written by said keys are set up, a general operator for carrying the set up numbers into said devices, and including a cross-bar, said 95 bar normally lying adjacent said keys, a series of dogs for preventing simultaneous depression of two keys, a lug normally tending to enter between said dogs and lock said keys, and means connecting the said lug and under the control of said cross-bar for normally holding said lug ineffective. 100

19. In a combined typewriting and computing machine, the combination with numeral keys and computing devices controlled thereby, of means for preventing simultaneous depression of said keys, comprising a series of members, a guideway in which said members normally loosely fit, said members being so arranged in said 110 guideway that the depression of a key interposes a part between said members, so that the members then completely fill said guideway, and prevent the actuation of a second key, a general operator for carrying numbers into the computing devices under the control of said keys, and means controlled by said general operator to interpose an element between said members in said guideway, to thereby completely fill said guideway, and thereby prevent the operation of 115 any keys at such time. 120
